(57) **CLAIM**

An ornamental design for an electronic article surveillance pedestal antenna, as shown and described.

DESCRIPTION

FIG. 1 is a front perspective view showing the new design of the receiver antenna;

FIG. 2 is a front elevational view thereof, the rear elevational view being a mirror image thereof;

FIG. 3 is a right side elevational view thereof, the left side elevational view being a mirror image thereof;

FIG. 4 is a top plan view thereof;

FIG. 5 is a front perspective view thereof, showing an alternate arrangement of antenna wire loops visible in the acrylic portion of the antenna; and,

FIG. 6 is a front elevational view of FIG. 5, the rear elevational view being a mirror-image thereof.

The broken line showing of the antenna wire loops is for illustrative purposes only and forms no part of the claimed design.
